UNITED STATES PATENT OFFICE.

ARTHUR ISHERWOOD, OF BOSTON, MASSACHUSETTS, ASSIGNOR TO THOMAS LEYLAND & CO., INC., OF READVILLE, BOSTON, MASSACHUSETTS, A CORPORATION OF MASSACHUSETTS.

CLOTH SPREADER OR EXPANDER.

Application filed September 23, 1926. Serial No. 137,246.

The invention is an improvement in the curved spreader or expander rolls that are employed in cloth spreading or expanding devices of the so-called bent-bar type. Forms of such devices are shown and described in U. S. Letters Patent No. 687,847, granted Dec. 3, 1901, for apparatus for distending textile fabrics; and No. 1,233,059, granted July 10, 1917, for cloth spreader or expander.

10 The said curved spreader or expander rolls are composed, respectively, of a transversely-extending curved, non-rotating, supporting rod or bar, and a series of blocks that are mounted in line with one another upon such 16 rod or bar with capacity to revolve upon the same. In some instances in practice the said blocks have annularly serrated peripheries. In other instances a tubular rubber covering surrounds the series of blocks. Through the 20 engagement of the cloth, in its passage, with the serrated peripheries of the blocks or with the exterior surface of the rubber covering the series of blocks or covered roll is caused to turn around the supporting rod or bar. By 25 reason of the curvature of the supporting rod or bar the revoluble blocks stationed in different portions of the curve rotate in planes which respectively mostly are inclined at different angles with relation to the direction of 30 movement of the web of cloth, those at one side of the middle line of the path of the web diverging in one direction laterally, and those at the other side of such middle line diverging in the opposite direction laterally. Consequently 35 the peripheries of the revolving blocks operate, as that of the rubber covering operates, in well-known manner to spread or expand the cloth transversely of its width in both directions laterally from its middle line.

40 Certain aims of the invention are to provide special features applicable to rolls in general of the class.

The invention includes features which are applicable to spreader or expander rolls, 45 either having a covering of frictional material or not as the case may be.

The relations of the invention, and the nature of the invention itself, will be understood readily from the following description, taken 50 in connection with the accompanying drawings, in which latter,—

Fig. 1 is a plan view of a Mycock expander.

Fig. 2 is a front elevation thereof.

Fig. 3 is a sectional view of a roll embodying 55 the invention.

Fig. 4 and Fig. 5 are views in section on lines 4, 4, and 5, 5, respectively, of Fig. 3.

In Figs. 1 and 2 curved spreading or expanding rolls are shown at 1, 1; and 2, 2, are side-supports for the opposite ends of the 60 curved non-rotating supporting rods 3, 3, of the said rolls. The other elements of the devices in general which are shown in the said views are or may be as heretofore, or as preferred, and are not involved in the invention. 65

Referring now, more particularly, to the features which are represented in Figs. 3, 4, and 5:—

Fig. 3 shows a portion of the length of a curved, non-rotating, supporting rod 3, and 70 shows mounted upon such portion a part of a series of blocks 4, 4. The said blocks are approximately cylindrical. They are hollow or shell-like, with hub-portions 41, 41, at their opposite ends. Within the central openings 75 of the said hub-portions the blocks are furnished with bushings 5, 5, of convenient bearing-material, for example metaline, fitting the supporting rod and adapted to turn thereon. Within the cavity or chamber is 80 located suitable means for containing a supply of lubricant. In Fig. 3 such means consists of washers 6, 6, within each block, located alongside the bushings. Preferably, 85 in practice, these washers are composed of felt, soaked with oil or otherwise charged with lubricant. As thus far referred to, the features are capable of being adopted in the case of the blocks of spreading or expanding rolls in general of the class to which the invention relates.

At 7, Figs. 3 and 5, is a tubular covering of flexible material having the frictional qualities which are required in order to enable the roll to be rotated by the contact of a traveling web of cloth therewith, and in order to enable it to spread or expand the cloth widthwise, and having also the characteristics which are requisite in order to enable the said covering, in its rotation in unison with the 100 said curved line of blocks to accommodate itself to the curvature of the said line. Rubber has the qualities and characteristics in question.

In the case of the illustrated construction 105 the peripheral portions of the blocks, and the interior portion of the covering 7 are shaped, suitably for interlocking driving engagement with each other, so as to cause the said blocks to turn or rotate in unison with the covering 110.

7 around the supporting rod 3 also, suitably to provide for movement of the blocks in the direction of the length of the covering, within the latter, in primarily assembling and combining the parts, and in subsequently making removals followed by reinstatement or substitution. Thus in the drawings each block is characterized by having longitudinal salient portions 42, 42, which are 10 distributed around the periphery of the block, and that the interior wall of the covering is shaped to conform to the peripheral contour of the blocks. As illustrated, the block is a polygon in cross-section, herein an 15 octagon, and the shape of the interior wall of the covering is the converse thereof. Not only does the interlocking engagement of the peripheries of the blocks with the interior of the covering provide for enforced unison rotation of the series of blocks and the covering, but the longitudinal disposition of the 20 salients and intermediates makes it practicable to insert the blocks successively within an end of the tubular covering, and to push 25 them along within the latter, lengthwise thereof, into the desired positions relative to the length of a roll and to one another. This renders it unnecessary to mold or otherwise form the covering upon the blocks so as to 30 become permanently attached thereto. The covering may be produced and supplied independently, and the blocks may be applied and assembled therein at convenience, or whenever the application and assembling are convenient or necessary. Removal and replacement of the blocks are made possible.

In this instance each end of the roll is fin-

ished off by means of an end-cap or ferrule 8, the radial annular portion of which surrounds a reduced end-portion, 421, of the corresponding terminal block 4, of the roll, while the peripheral shell of such end-cap or ferrule surrounds the end-portion of the covering. This end-cap or ferrule is held in place by means of rivets 9, 9, Figs. 3 and 4, 40 45 which are disposed parallel with the supporting rod. The inner ends of these rivets are entered into threaded holes in the adjacent end of the block. The stems of the rivets occupy notches in the inner edge of the said 50 radial annular portion, whereby the cap or ferrule is prevented from rotating relative to the roll. The flanges of the heads of the rivets engage with the radial annular portion to hold the cap or ferrule from separating from 55 the end block and the end of the cover.

In order to prevent displacement of the felt washers 6 within the blocks, the latter are formed with annular projections, 422, 422, between which and the hub portions 41, 41, of the blocks, the felt washers are confined.

What is claimed as the invention is:—

In a spreader or expander roll, the combination with a non-rotating supporting rod, of 65 a series of substantially-cylindrical or barrel-shaped blocks mounted thereon, each of said blocks hollow and furnished at its ends with applied bearings contacting with the said rod, and lubricant-holding packing 70 within the said blocks between the said bearings.

ARTHUR ISHERWOOD.
